WINDING APPARATUS

William H. Franzmann, Hamilton, Ohio, assignor
to The Hamilton Tool Company, Hamilton,
Ohio, a corporation of Ohio

Application January 25, 1951, Serial No. 207,817

5 Claims. (Cl. 242—75)

1

This invention relates to winding devices and more particularly to a device for winding material under conditions of substantially uniform tension.

An object of the invention is to provide a simple, compact, highly efficient device which may be utilized to rewind with substantially uniform tension one or more continuous webs of material.

Another object of the invention is to provide a winding apparatus which includes means for automatically and continuously controlling the tension of the material being wound.

A further object of the invention is to provide a winding apparatus having the hereinabove described characteristics which includes tension applying means engageable with and supported by the web of material prior to being wound.

Still a further object of the invention is to provide a winding apparatus wherein the means for applying tension to the web or webs of material is adjustable, thereby greatly enhancing the flexibility of the device.

Another object of the invention is to provide a winding device which includes a shaft upon which one or more continuous webs of material may be wound under conditions of substantially uniform tension, wherein the driving torque applied to the shaft is selectively variable through means actuated by the web tension for automatically correlating the torque to the tension requirements of the web.

Still another object of the invention is to provide a rewinder device which is portable in the sense that it may be associated with a wide variety of other devices from which one or more continuous webs are drawn for rewinding, thereby greatly enhancing its utility.

Still a further object of the invention is to provide a rewinder having the hereinabove described characteristics and which includes a plurality of guide rollers over which the individual continuous webs of material are fed after being subjected to the action of tensioning means and prior to being wound, said guide rollers being inclined relative to one another for effecting uniform lateral spacing of the adjacent edges of adjoining rolls of rewound material.

Another object of the invention is to provide a winding apparatus wherein the tension on the web is substantially constant whether the web is stationary, is being inched, or is running at any speed. This feature eliminates the likelihood of slack developing in the web when it is not in motion and eliminates web looseness heretofore encountered during start-outs of other

types of rewinding apparatus with which I am familiar.

These and other objects are attained by the means described herein and as disclosed in the accompanying drawings, in which

Fig. 1 is a side elevational view of a winding apparatus embodying the teachings of the present invention.

Fig. 2 is a front elevational view of a slightly modified form of the apparatus of Fig. 1.

Fig. 3 is an enlarged view, partly in section, of a detail of the driving and control mechanism of the device.

With reference now to Fig. 1, the numeral 10 denotes generally a continuous web of material which it is desired to rewind under conditions of substantially uniform tension.

At the outset it should be understood that web 10 may be drawn from a roll, not illustrated, or it may, by way of example, represent the web drawn from a rotary printing press, slitter mechanism, combination rotary press and slitter device, or any other type of device from which a continuous web, printed or otherwise, is discharged.

Solely by way of example, it will be assumed that web 10 is being discharged from a rotary press having associated therewith a plurality of laterally spaced cutting knives 12 which sever the web into a series of strips of lesser width. Three such strips have been denoted by the numerals 14, 16 and 18.

A rotatable shaft 20 upon which material 10 is to be wound is suitably journaled in spanning relationship with a pair of similar, laterally spaced side or end members 22.

With particular reference now to Fig. 3, it will be noted that shaft 20 is adapted to be driven by gear 23 secured to and carried by drive shaft 24 suitably journaled in boss 26 of end element 22. A rotatable armature 30 is secured to and carried by shaft 24 being keyed thereto as at 32. A rotatable field assembly denoted generally by the numeral 34 may be rotatably mounted relative to armature 30 and shaft 24 on bearings 36, the inner races 37 of which engage the outer periphery of shaft 24, the outer races 39 of which are received within and supportingly engage axial bore 38 provided in internal hub 40 of the rotatable field assembly.

A field coil denoted generally by the numeral 42 comprises part of the rotatable field assembly, said coil being electrically connected to commutator rings 44 and 46 carried by hub 48.

A suitable source of power such as, by way of example, an electric motor 50, may be utilized

for driving field assembly 34 at a substantially uniform speed. Motor 50 may be suitably secured by bracket 52 to portions of end member 22, thereby disposing drive pulleys 54 in vertical alignment with driven pulleys 56 of the rotatable field assembly.

A housing 58 may be utilized to inclose portions of the field assembly, said housing being mounted to a bracket 60 secured as at 62 to member 22, as illustrated.

The present invention is neither directed to nor concerned with the particular structural details of the electromagnetic clutch arrangement hereinabove described and as more fully illustrated in Fig. 3, said device being commercially available from several manufacturers.

The torque imparted to shaft 24 is a function of the magnetic coupling effected between armature 30 and the rotatable field assembly 34. The magnetic coupling is a function of the field strength of coil 42, which is a function of the voltage impressed thereon.

Voltage impressed upon field coil 42 may be supplied through conductors 64 and 66, wherein conductor 64 is electrically connected to brush 68 which engages commutator ring 44.

Conductor 66 is connected to brush 70 through a pair of series connected rheostats denoted generally by the numerals 72 and 74 whereby the voltage delivered to field coil 42 may be selectively varied.

With particular reference now to Figs. 1 and 2, it will be noted that a dancer roll 78 is supported by web 10 of the material, said dancer roll being rotatably mounted between a pair of laterally spaced arms 80. Arms 80 are pivotally mounted as at 82 to the upper end of side members 22.

As illustrated in Fig. 1, dancer roll 78 and arms 80 are shiftable between the fully raised and lowered positions indicated in dotted outline, the particular position of the dancer arm being determined by the tension in web 10, it being understood that the greater the tension the greater the elevation of dancer roll 78.

The degree of tension applied to web 10 is a function of the torque applied to shaft 20 on which the web of material 10 is to be rewound. The torque required to rotate shaft 20 increases proportionately as the diameter of the roll of material wound thereon increases, wherefore it is necessary to increase the torque delivered to shaft 20 as material is wound thereon.

One of the primary objects of the present invention is to provide simple yet highly effective means for automatically and simultaneously applying a predetermined tension to web 10 and of utilizing the tension applying means for controlling the torque output of the shaft driving mechanism. This has been accomplished by providing a segment gear 90 in driven relationship with one of arms 80 whereby movement of the arm about axis 82 will result in rotation of the segment gear about the same axis. A pinion gear 92 is secured in driving relationship with shaft 94 of rheostat 74 whereby oscillation of the dancer roll will result in rotation of shaft 94, thereby actuating arm 96 of the rheostat for automatically controlling the voltage applied to field coil 42.

From the foregoing, it will be noted that if it be assumed that the dancer roll be positioned in the uppermost position as indicated in the dotted lines of Fig. 1 at the start of a winding operation, wherein the degree of tension applied to

web 10 has been predetermined and controlled by means of weights 100 secured to and carried by shaft 102 pivotally secured as at 104 to the outer end of one or both of arms 80, any lessening of the torque will result in a lowering of the dancer roll, for a given tension. However, lowering of the dancer roll will result in actuation of rheostat 74 via segment gear 90, pinion 92 and shaft 94 whereby the amount of resistance in the field coil circuit will be decreased, thereby increasing the voltage applied to the field coil for increasing the degree of magnetic coupling effected between the rotatable field assembly 34 and armature 30. In this manner the torque delivered to shaft 20 is correlated to tension requirements of the web.

In the preferred embodiment of the invention sudden movement of arms 80 is precluded by means of a suitable damping assembly, such as, by way of example, a shock-absorber 120 secured as at 122 relative to portion 124 of end member 22. Rod 126 of the shock-absorber may be secured as at 128 relative to arm 80.

With particular reference now to Figs. 1 and 2, the numerals 130, 132 and 134 denote laterally spaced rollers mounted for rotation about axes 136, 138 and 140, respectively, wherein said axes are relatively inclined by an amount less than one degree, such as, by way of example, from .2 to .5 degree.

Preferably axis 138 may be in a substantial horizontal plane, in which event axis 136 may be inclined in one direction with reference thereto whereas axis 140 may be inclined in the opposite direction with reference thereto. I have found that by thus slightly inclining the axes of rotation of rollers 130, 132 and 134 the adjacent edges of the adjoining webs 14, 16 and 18 severed from web 10 will be uniformly spaced, as clearly illustrated in Fig. 2. In this manner I have provided simple yet highly effective means for providing lateral separation of adjacent edges of adjoining rolls, thereby obviating any tendency for the adjacent edges of adjoining rolls to overlap incident to a rewinding operation. Such overlapping has presented a serious problem to the industry, particularly in those instances wherein it has been desirable to simultaneously rewind at high speeds a plurality of webs in side-by-side relationship.

It should be understood that if desired axis 136 or 140 may be considered as the horizontal axis, in which event the other two axes would be inclined relative thereto for effecting the desired separation of the adjacent edges of adjoining rolls of material wound onto shaft 20. It should further be noted that although I have illustrated three such rolls, 130, 132 and 134, such illustration is exemplary in nature rather than restrictive.

With particular reference now to Fig. 1, it will be noted that web 10 is caused to pass over a pair of idler rolls denoted generally by the numerals 150 and 152 for thereby effecting suspension of dancer roller 78. In most instances idler rolls 150 and 152 will comprise part of a rotary printing press, slitting mechanism, or other suitable device from which web 10 is drawn for rewinding, however it should be noted that if desired, idler rolls 150 and 152 may be secured to and carried by a suitable bracket or brackets, not illustrated, secured to end members 22.

It should be noted that composite web 10, which has been severed into webs 14, 16 and 18 by slitting knives 12 will be fed over rolls 150, 78, 152

and to rolls 130, 132 and 134 with the adjacent edges of adjoining strips in substantial abutting relationship. These abutting edges are, however, neatly and uniformly laterally separated after webs 14, 16 and 18 have been caused to pass over their respective rolls 130, 132 and 134.

With reference to Figs. 2 and 3, the numeral 160 denotes the control arm of manually operable rheostat 72, said arm, as clearly illustrated in Fig. 3, being series connected with the resistance element 162 of the pinion driven rheostat 74. The purpose of providing a manually controllable rheostat 72 in series with the pinion driven rheostat 74 is to enable an operator to adjust the manual rheostat, at the start of a rewinding operation, whereby the desired torque will be delivered by shaft 20 with all of the resistance of the pinion driven rheostat in series with field coil 42. Then, as the tension in web 10 tends to decrease as the diameter of the roll of rewound material increases about shaft 20 (which increase in diameter would, but for the actuation of the pinion driven rheostat 74, result in a decrease in the torque applied to shaft 20), the resultant lowering of dancer roll 78 effects an automatic actuation of rheostat 74 for increasing the voltage in field 42, thereby increasing the torque delivered through the electromagnetic clutch assembly to shaft 20.

It will be noted that the tension applied to the web, or webs of material by the dancer roll will be constant throughout all positions of the dancer roll assembly. The reason that the dancer roll assembly will slowly and gradually shift from the uppermost to the lowermost positions indicated in dotted outline of Fig. 1 is not because of a change of the tension in web 10, but for the following reason, viz., as the diameter of the roll of material being wound upon shaft 20 increases, more torque is required to rotate the shaft. Since the tension applied to the web of material by the dancer roll assembly is constant, any decrease in torque will result in a lessening of the pull on the web with a corresponding lowering of the dancer roll assembly which as has hereinabove been fully explained is utilized to increase the torque delivered by the electromagnetic clutch to shaft 20.

The dancer roll assembly will not be elevated to its original fully elevated position incident to the application of a greater turning torque to shaft 20 incident to control of the voltage characteristics of field 42 of the field assembly by reason of actuation of the pinion driven rheostat 74, incident to lowering of the dancer roll assembly, since to elevate the dancer roll assembly to its initial position would require the application of a torque in excess of that required to maintain the desired tension in web 10. Therefore, the dancer roll assembly will gradually be lowered from an upper to a lower position, while maintaining a uniform load or tension on web 10.

In the preferred embodiment of the invention the zone of travel of the dancer roll assembly is from 15 degrees above to 15 degrees below a horizontal axis at right angles with axis 82.

By reason of the electromagnetic clutch drive I am able to interrupt the feeding of web or webs 10 from a printing, slitting or other device from which the web is being drawn without having to stop motor 50 which drives the rotating field assembly of the clutch or without having to manually manipulate or adjust the control circuit of field 42. When the movement of web 10 is thus

interrupted, armature 30 will be stopped by reason of its connection through shaft 24, gear 23 and pinion 188 to shaft 20, whereby slippage will occur between field assembly 34 and armature 30 while the torque delivered to shaft 20 will remain uniform even though the shaft be held stationary.

The dancer roll assembly will, of course, maintain the stationary web under the same tension to which it was subjected while in motion. Release of web 10 for permitting it to be fed onto shaft 20 will result in the immediate rotation of armature 30 whereby the formation of a slack condition in web 10 will be positively precluded.

With reference now to Figs. 1 and 2, it will be noted that the opposite ends of shaft 20 are received within suitable journals provided in end members 22, said journals preferably including a shaft block 190 pivoted as at 192 relative to the supporting frame for facilitating quick, easy mounting and demounting of shaft 20. In actual practice, several shafts, each including a pinion 188 engageable with drive gear 23, may be utilized in order that one shaft may be operatively associated with the rewinder during those periods of time when the roll or rolls of material previously wound may be removed from a prior shaft.

To remove a shaft all an operator need do is to withdraw block pin 194 for permitting the shaft blocks 190 to be swung outwardly for releasing the shaft ends from the journals in which they were rotatably secured. Another shaft may then be mounted by closing blocks 190 whereupon the machine is again ready for use.

It should be understood that the rolls of material mounted upon shaft 20 are actually supported thereon by tapered end plugs which engage the shaft, as well known in the industry.

From the foregoing, it will be noted that I have thus provided a simple, yet highly effective means for applying uniform tension to a web or webs of material being wound upon a rotatable shaft driven through an electromagnetic clutch assembly, wherein the output of the drive assembly is controlled by the tension applying means.

It should be understood that various changes and modifications in the structural details of the device may be made within the scope of the appended claims without departing from the spirit of the invention.

What is claimed is:

1. In a rewinding apparatus, the combination of rotatable means upon which a plurality of laterally spaced rolls of material are adapted to be wound, means for driving said rotatable means including an electromagnetic clutch, means for rotatably mounting a roll of material to be slit and rewound, means for slitting the material into continuous strips of lesser width, means for simultaneously applying a predetermined tension to said strips comprising a member extending across and suspended from said strips, means for utilizing movement of said member for varying the magnetization of said clutch, and a plurality of idler rollers, one for each strip of material, over which a strip passes prior to being wound onto said rotatable means, wherein the axis of rotation of each of said rollers is inclined relative to the other for effecting uniform lateral separation of adjacent edges of adjoining strips wound on said rotatable means.

2. In a rewinding apparatus, the combination of a frame including a pair of laterally spaced end members, a shaft upon which a continuous web of material of substantial width is adapted

to be wound, means for securely though releasably mounting said shaft in spanning rotatable relationship with said end members, means including an independently driven, continuously operable electromagnetic clutch for driving said shaft, a dancer roll assembly pivotally mounted in spaced spanning relationship relative to said end members, an idler roll over which the web passes, means for feeding the material to be rewound from said idler roll under said dancer roll and in supporting relationship therewith, a second idler roll over which the web passes from the dancer roll and thence to said shaft, said dancer roll applying a predetermined tension to the material, and means actuated by movement of said dancer roll for varying the magnetization of said clutch for maintaining the desired tension on the material being rewound at all speeds and when stationary.

3. In a rewinding apparatus for a plurality of continuous strips severed from a continuous strip of greater width, the combination of a rotatable shaft upon which the individual strips are wound in laterally spaced individual rolls, means including an independently driven, continuously operable electromagnetic clutch for driving said shaft, means for simultaneously applying a predetermined tension to the individual strips including a dancer roll spanning and suspended from said strips, means for utilizing elevational changes of the dancer roll for varying the degree of magnetization of said clutch for varying the torque applied to said shaft, and a plurality of freely rotatable idler rollers, one for each strip of material, over which a strip passes prior to being wound onto said shaft, the axis of rotation of each of said rollers being inclined relative to the others for effecting uniform lateral separation of the adjacent edges of adjoining strips wound on said shaft.

4. In a rewinding apparatus, the combination of a frame including a pair of laterally spaced end members, a shaft upon which a plurality of laterally spaced rolls of material are adapted to be wound, means for securely though releasably mounting said shaft in spanning rotatable relationship with said end members, means including an independently driven continuously operable electromagnetic clutch for driving said shaft, means for rotatably mounting a roll of material to be slit and rewound, means for slitting the material into continuous strips of lesser width, a dancer roll assembly pivotally mounted in spaced spanning relationship relative to said end members, means for feeding the continuous strips severed from the web of material being rewound under said dancer roll and in supporting relationship therewith and thence to said shaft,

said dancer roll simultaneously applying a predetermined tension to said strips, and means actuated by movement of the dancer roll for varying the magnetization of the clutch, a plurality of rollers one for each strip of material over which the strip passes prior to being wound onto the shaft upon which the material is rewound, said rollers being rotatably mounted in spanning relationship with said end members above the shaft upon which the material is rewound, the axis of one of said rollers being in substantial parallelism with the axis of said shaft, and the axes of the other rollers being inclined in opposite directions by less than one degree relative to the axis of said first roller and to one another for providing lateral separation of adjacent edges of adjoining continuous strips severed from the roll of material being rewound.

5. A rewinding apparatus comprising the combination of a frame, a shaft rotatable in said frame upon which a continuous web of material of substantial width is adapted to be wound, shaft rotating means comprising an electromagnetic clutch including a rotatable armature mechanically coupled to said shaft and a rotatable field assembly, means for independently and continuously driving the field assembly at a substantially constant rate, a source of voltage for the field of said field assembly for effecting a magnetic coupling between the rotatable field assembly and armature, a rheostat in the circuit of said field, a pair of arms pivotally secured to said frame, a dancer roll spanning and rotatably mounted between said arms, an idler roll over which the web passes, means for feeding the material to be rewound from said idler roll under said dancer roll and in supporting relation therewith, a second idler roll over which the web passes from the dancer roll and thence to said shaft, said dancer roll applying a predetermined tension to the material, and means actuated by movement of said arms relative to the frame for actuating said rheostat for varying magnetization of said clutch for maintaining the desired tension on the material being rewound at all speeds and when stationary.
